UNITED STATES PATENT OFFICE.

GUSTAV L. HEYMAN, OF CARLISLE, KENTUCKY.

DETACHABLE PAD FOR BREAST-STRAPS.

SPECIFICATION forming part of Letters Patent No. 532,732, dated January 15, 1895.

Application filed September 7, 1894. Serial No. 522,354. (No model.)

To all whom it may concern:

Be it known that I, GUSTAV L. HEYMAN, of Carlisle, in the county of Nicholas and State of Kentucky, have invented a new and useful 5 Improvement in Detachable Pads for Breast-Straps, &c., of which the following is a specification.

My invention is designed to provide a cheap, simple, and easily applied pad, which may be 10 quickly fitted to any breast strap, breeching, or belly-band, and which being always smooth and pliable will prevent chafing and keep the bearing surfaces of the animal cool and comfortable.

15 It is an improvement in pneumatic pads, or that form of pad which is inflated with air, and it consists of a pad having at its marginal edges overlapping lips, hooks, or claws, into which the breast strap is inserted by being 20 rolled or bent longitudinally and then allowed to expand and straighten out beneath the lips, hooks or claws as hereinafter fully described.

Figure 1 is a side view of my pad applied to a breast strap. Fig. 2 is an enlarged cross 25 section of the same through line 2—2; and Fig. 3 is a side view of a modification.

In the drawings, A represents the breast strap, and B is the pad. This pad is composed of soft rubber with a tightly sealed air 30 chamber b in the middle of it that forms a soft pliable bearing surface b' of rounding shape where it comes in contact with the animal. This air chamber may be filled with air and 35 permanently sealed, or it may, if desired, have a screw nipple so that it may be recharged by a small air pump from time to time after the manner of a bicycle tire.

At the edges of the pad beyond the middle air chamber the material is thickened so as to 40 give it more or less stiffness and these thickened edges are formed in one piece into over-

lapping lips c c that project upon the side opposite the bearing surfaces and are designed to overlap and thus hold the pad upon the edges of the breast strap. These overlapping 45 edges c may be constructed as continuous lips as shown, or, if preferred, they may be arranged at intervals along the length of the pad as hooks or claws, as shown in Fig. 3. When constructed as a continuous lip the 50 latter will be cut away at the points where it passes the supporting strap A'.

In applying this pad to the breast strap, the latter is bent or rolled longitudinally, as shown in dotted lines, and is then allowed to 55 expand into and between the overhanging lips or claws, which then securely hold the two together.

This pad attachment is universal in its application, is easily and quickly applied or removed, and involves no alteration of nor injury to any part of the harness to which it may be applied. It is also to be sold as a 60 separate article of manufacture, and may be applied by any one to the harness without 65 calling in the services of a harness maker.

I am aware that pneumatic pads are not broadly new, and therefore claim only my 66 special construction and arrangement.

Having thus described my invention, what 70 I claim as new, and desire to secure by Letters Patent, is—

A harness pad consisting of a rubber air chamber formed in one piece with marginal overlapping lips or claws projecting upon the 75 opposite side from the bearing surface of the pad substantially as and for the purpose described.

GUSTAV L. HEYMAN.
